UNITED STATES PATENT OFFICE.

GEORGE A. PRALL, OF KEOSAUQUA, IOWA.

SCUTTLE-LADDER.

1,109,460.

Specification of Letters Patent.

Patented Sept. 1, 1914.

Application filed February 25, 1914. Serial No. 820,987.

To all whom it may concern:

Be it known that I, GEORGE A. PRALL, a citizen of the United States, residing at Keosauqua, in the county of Van Buren and State of Iowa, have invented new and useful Improvements in Scuttle-Ladders, of which the following is a specification.

The invention relates to an invisible stairway, and more particularly to the class 10 of combined trap door ladders.

The primary object of the invention is the provision of a structure of this character wherein the ladder is so mounted on the trap door that on the opening of the same the ladder will become lowered to permit the use thereof in gaining entrance to a loft, attic or overhead space, and on the closing of the trap door the said ladder will be concealed from view, and thus be 20 out of the way to give maximum space in a room, hallway or the like.

Another object of the invention is the provision of a structure of this character wherein the ladder and the trap door are 25 balanced to permit the easy manipulation thereof and to effect an automatic action, thus rendering the loft, attic or the like readily accessible in event of a fire breaking out therein, or should it be desired to 30 utilize its space for storage purposes.

A further object of the invention is the provision of a structure of this character which is unique and attractive in its make-up, novel in form, and possesses the advantages of an ordinary stationary stairway, yet occupying minimum space, and in addition having the advantage of being invisible when not in use.

A still further object of the invention is 40 the provision of a structure of this character which is simple in construction, easy of action, reliable and efficient in operation, and inexpensive in manufacture.

With these and other objects in view, the 45 invention consists in the construction, combination and arrangement of parts as will be hereinafter fully described, illustrated in the accompanying drawing, and pointed out in the claims hereunto appended.

50 In the drawings:—Figure 1 is a vertical sectional view through an attic and a room beneath the same, showing the combined trap door and ladder constructed in accordance with the invention in normal position.

55 Fig. 2 is a similar view, showing the trap door lowered and the ladder let down. Fig.

3 is a top plan view with the parts shown in the position in Fig. 1. Fig. 4 is a sectional view on the line 4—4 of Fig. 1. Fig. 5 is a fragmentary longitudinal sectional view through the ladder and trap door, showing in detail the catch.

Similar reference characters indicate corresponding parts throughout the several views in the drawings.

Referring to the drawings in detail, A designates a room, B the attic above the same, and C an opening forming communication therebetween, the same being fitted with a door frame D normally closed by 60 means of a trap door E of any ordinary well-known construction, and connected thereto by the usual hinges F so that the trap door can be readily swung to open or closed position.

Arranged at one end of the door frame D at opposite sides thereof within the attic B are vertical uprights or posts G which extend upwardly to the roof rafters and are fixed thereto in any suitable manner. Fixed 70 to the inner sides of the uprights or posts G spaced from the lower ends thereof are guide blocks 10 having beveled ends 11 against which work the side rails 12 of a ladder H including the cross steps 13 which 80 are mounted in the side rails 12 as usual, it being understood of course that the uprights or posts G are arranged at the end of the door frame D to which the trap door E is hinged so that the ladder H will freely 90 slide against the inner face of the said trap door E when being opened or closed.

Fixed transversely of the trap door E near its opposite free end is a guide cleat 14 having hook limbs 15 which embrace the 95 side rails 12 of the ladder H for guiding the same when the trap door is being swung to open or closed position. On the head end of the ladder H and fixed to the outer sides of the side rails 12 are abutment blocks 16 100 which are adapted to engage the uprights or posts G when the ladder has been lowered or extended downwardly into the room A for use, as shown in Fig. 2 of the drawings, so as to prevent the slipping of the said ladder or the pulling of the same out of the opening C through the door frame D therein.

Fixed to one of the posts or uprights G and block 10 thereon are respective upper 110 and lower guide pulleys 17 and 18, over which is trained a cable 19, one end of which

is fixed to the ladder H, while its opposite end carries a balancing weight 20, and in this manner the trap door E and the ladder H are properly balanced for the convenient working of the same when the said trap door is opened or closed.

Carried at the inner face of one side rail 12 of the ladder H at the foot end thereof is a catch 21, the same being pivotally supported and is adapted to engage a keeper plate 22 mounted on the inner face of the trap door E so that the ladder H can be locked against lowering movement on the opening of the trap door until the catch 21 has been released from the plate 22, whereupon the said ladder H can be extended into the room so that a person can ascend the same for entrance to the attic B from the said room A, or vice versa.

20 It will be apparent that when the trap door E has been closed, the ladder H is projected into the attic and is invisible from the room A, and also will be out of the way so as not to occupy any space therein.

25 From the foregoing it is thought that the construction and manner of use of the device will be clearly understood, and therefore a more extended explanation has been omitted.

30 What is claimed is:—

1. The combination with a trap doorway and swinging door therefor, of a ladder movable through the doorway, guide cleats fixed to the door and engageable with the side rails of the ladder, a railing fixed to the

doorway and rising above the plane thereof, vertical posts rising from the railing and having cut-away portions for receiving the side rails of the ladder and forming abutments therefor when the ladder has been extended through the doorway and the door opened, and weighted balancing means supported by the uprights and connected with the ladder.

2. The combination with a trap doorway and swinging door therefor, of a ladder movable through the doorway, guide cleats fixed to the door and engageable with the side rails of the ladder, a railing fixed to the doorway and rising above the plane thereof, vertical posts rising from the railing and having cut-away portions for receiving the side rails of the ladder and forming abutments therefor when the ladder has been extended through the doorway and the door opened, weighted balancing means supported by the uprights and connected with the ladder, slotted keeper plates mounted in the inner face of the door, and gravity catches pivotally mounted on the side rails of the ladder for engagement in the keeper plates to lock the ladder against sliding movement in the guide cleats on the opening of the door.

In testimony whereof I affix my signature in presence of two witnesses.

GEORGE A. PRALL.
